[57] CLAIM

The ornamental design for a chandelier, as shown and described.

DESCRIPTION

FIG. 1 is a front perspective view of a chandelier showing my new design;

FIG. 2 is a right side elevational view of the chandelier, the left side elevational view being a mirror image;

FIG. 3 is a front elevational view of the chandelier, the rear elevational view being a mirror image;

FIG. 4 is a top plan view of the chandelier; and,

FIG. 5 is a bottom plan view of the chandelier.

The broken lines showing of the lights is for illustrative purposes only and forms no part of the claimed design.
